C. E. BEACH

SIGNALING SYSTEM

Filed Oct. 9, 1919

UNITED STATES PATENT OFFICE.

CLARENCE E. BEACH, OF BINGHAMTON, NEW YORK.

SIGNALING SYSTEM.

Application filed October 9, 1919. Serial No. 329,603.

To all whom it may concern:

Be it known that I, CLARENCE E. BEACH, a citizen of the United States, residing at Binghamton, county of Broome, and State 5 of New York, have invented certain new and useful Improvements in Signaling Systems, of which the following is a specification.

This invention relates to signaling systems comprising a plurality of signal initiating stations and signal manifesting stations, and is particularly adapted for use in signaling systems having a plurality of code signal initiating stations and signal manifesting stations, some of which manifesting stations are responsive to all of the initiating stations, and other of which manifesting stations are responsive to only a certain one or more initiating stations. Such manifesting stations as are responsive to all initiating stations will be hereinafter referred to as "general manifesting stations," and those so associated with certain initiating stations that their responsiveness to signals is controlled by such stations will be hereinafter referred to as "associated manifesting stations."

It is well known that, for signaling systems of certain types,—such as, for example, 30 certain thermostatically controlled systems,—normally open contacts can be more readily and dependably controlled, than normally closed contacts, for the purpose of giving warning of the development of abnormal or 35 dangerous conditions. It is also well recognized that effective electrical operating conditions may be most dependably maintained in systems which are so arranged that, suitable warning will be automatically given, in 40 the event of the rupture of any current path the continuity of which is vital to the manifestation of signals responsive to the actuation of signal initiating circuit closing contacts, such as have been hereinbefore referred to.

In view of the foregoing, systems have heretofore been devised in which normally separated contacts have been arranged to shunt out windings of a normally energized 50 electro-magnet, for the purpose of de-energizing such magnets and thereby causing the transmission of an intended signal. Such systems, when suited for the use of a

plurality of code signal initiating stations, have employed complicated mechanisms and circuit arrangements for the purpose of preventing activity of all of the signal transmitting stations in response to circuit breaks, such as those incidental to the transmission of a signal from any one initiating station; because such activity of all stations would impair or destroy the effectiveness of the transmission of an intended signal. Such prior systems have usually employed numerous independent current sources at 60 scattered locations; the disadvantages of which, as compared with a common or centralized current source for supplying all parts of the system, are well understood by those skilled in this art.

Practical considerations frequently require the extension of a signaling circuit, of the character indicated, so as to cover an extensive territory and to include many signal initiating stations. The resistance of the 75 line conductors of such systems is necessarily comparatively high, such conductors are frequently of very limited current carrying capacity, and limitations are very generally enforced as to the maximum electromotive 80 force which shall be applied to such signaling systems; all of which limitations are especially salient when underground cable conductors are made part of such systems. For these reasons, the energy is very limited 85 which may be transmitted from a common current source for the excitation of the tripping magnets of a plurality of initiating stations; thus making the effectiveness of the utilization of such energy an important aim.

When such systems are provided with initiating stations having normally energized shuntable tripping magnets, reliability of service demands that a retractile force shall be provided which exceeds, by a suitable 95 factor of safety, that which will barely overcome all residual magnetism, and trip the mechanism of such station even after such mechanism has stood unused for a long period. For like reasons, the pull of such 100 tripping magnets should exceed such retractile force with a like factor of safety.

It is thus evident that the tripping magnets of such systems must, in order to afford a like factor of safety, absorb more energy 105 than would be required in the case of a nor-

mally de-energized magnet, the pull of which need only to be sufficient to act, with but a single factor of safety, to trip the mechanism and to overcome the retractile 5 force which is barely sufficient to overcome any residual magnetism and to prevent unintended actuation of the mechanism.

An object of this invention is to provide a system in which the transmission of signals may be initiated by the closure of any of several pairs of normally open contacts, and in which a fully effective electrical test will be normally maintained through all current paths, (including magnet windings) 10 which are essential to the initiation and transmission of a signal from any initiating station to the general manifesting mechanism of such systems, except from one to the other of contacts of said pairs through 15 the current paths which are only closed when such contacts have been actuated in a manner intended to cause the transmission of a signal.

Another object is to provide such a system 20 in which the resistance of the effective current path will not be increased, and will not be objectionably decreased, by any adjustment or revision of said path such as is intended to cause the operation of a transmitting station therein, to the end that the 25 operation of manifesting mechanism included in such current path, such as, for example, vibrating shunt bells, will not be noticeably affected by any such adjustment or 30 revision.

A further object is to provide, in such a system, facilities for suitably controlling a desired number of normally unresponsive manifesting stations, individually or in 35 groups, by means of suitable clock-work trains at initiating stations associated with such manifesting stations, so that, when a signal has been transmitted a desired one or more times by any one of such trains, a pre-determined manifesting station or group of 40 such stations will be rendered responsive to the current flow in the signaling circuit, so that the manifesting station or stations thus rendered responsive to the signaling circuit 45 may assist in guiding those who respond to the signal transmitted by such train to the locality of the origination thereof, and may apprise persons in that locality that a signal 50 has been transmitted therefrom.

55 A further object is to provide construction and arrangement of such controlling facilities whereby a continuous warning will be given by an associated manifesting station whenever, and so long as, the train of 60 any manifesting station is unwound to an extent which may prevent the transmission of its intended code signal.

65 A further object is to provide construction and arrangement of such controlling facilities whereby the loss of a signal cannot re-

sult from the change of circuit conditions resulting from such facilities being brought into action incident to the transmission of such signal, even in the event of any electrical defect in such facilities.

70 A further object is to provide construction and arrangement of such controlling facilities whereby the continuity of the signaling circuit will not at any time be dependent upon the closure of normally open contacts, 75 for reasons well understood by those skilled in this art.

80 A further object is to provide such a system in which a suitable number of initiating and manifesting stations may be supplied by a single series circuit, together with means for increasing the electromotive force of the current source of such circuit during the 85 transmission of signals and thereafter until the line current flow has been restored to not less than a predetermined value, to the end that ample electromotive force will be available for overcoming the resistance of such associated manifesting stations as may be operatively included in such circuit during 90 the transmission of signals therein.

95 Other objects are to simplify such systems, to render them more durable and more reliable in operation, to decrease their cost of installation, and to decrease the cost of manufacture of instruments employed therein.

Still other objects together with their inherent advantages will be in part obvious and in part hereinafter specifically set forth.

100 In constructing the various features of this invention, a normally closed signaling circuit is employed, and desired signal initiating and manifesting stations are connected in said circuit, together with a suitable current source; each of said initiating stations 105 having a normally wound train equipped with means including make and break contacts for transmitting distinctive code signals one or more times, together with an electro-magnet for tripping said train; and 110 means being associated with each initiating station for controlling the effective energization of such magnets.

115 The controlling means associated with each transmitting station comprises one or more pairs of normally open contacts, the contacts of each pair being arranged for desired manual or automatic operation, to be closed when it is desired to energize the tripping magnet of the initiating station associated therewith.

120 To the end that a fully effective electrical test may be maintained throughout all essential current paths (as hereinbefore more explicitly defined), the code signaling contacts, the windings of the tripping magnets of the various initiating stations and each of the contact members of the controlling means associated therewith are serially included in the normal current path of said 125

circuit; so that inasmuch as the entire normal current flow passes through all of said windings and contacts, any disconnection of or break therein will interrupt the flow of 5 said current therethrough, and thereby cause a suitable warning to be given by the manifesting mechanism included in said circuit.

In order to render the tripping magnets of the various initiating stations unresponsive to breaks in the signaling circuit, and for the further purpose of enabling the pull of such magnets to be directly and efficiently utilized for releasing or tripping the mechanism associated therewith,—such magnets 10 are provided with differential windings, which are so proportioned and connected that, when the normal line current is passing through both, the resulting magnetic fields substantially neutralize each other; so that 15 such magnets are not energized when the line current is flowing through both windings thereof.

For the purpose of rendering the said magnets responsive to the associated controlling means contacts,—each pair of said contacts are connected at one side and the other, respectively, of the leads to one of the differential windings of the magnet of the associated initiating station, so that, when said 20 contacts are closed, one of the windings of such magnets will be short-circuited, thus enabling effective energization of such magnet to be accomplished by current flow through the other of said windings.

35 From the foregoing it is apparent that the resistance of the effective current path is not increased by such a closure of controlling contacts, but is somewhat decreased, so as to increase the current flow through the 40 winding which is not shunted, and thus more effectively energize the tripping magnet; while not decreasing the resistance of the effective current path (and hence not increasing the current flow) to an extent 45 which would noticeably affect the operation of any manifesting mechanism (such as, for example, vibrating shunt bells) which are connected in said current path upon the occasion of such a contact closure.

50 In cases when it is deemed to be desirable to provide a local manifestation to assist those who respond to signals in proceeding directly to the locality of the origination thereof, and for the further purpose of giving 55 a continuous warning whenever the train of any initiating station has run down to more than a predetermined extent, manifesting stations are associated with signal initiating stations and so controlled there- 60 by as to become active after predetermined response of such initiating stations to the controlling means associated therewith.

In order to render such manifesting stations operable by the current source of the 65 signaling circuit,—such stations are serially

included in said circuit, and are of such construction and arrangement as to be suitably operable by the normal current flow in said circuit, and so that, in operating, they will not objectionably affect the continuity 70 of such current flow. Continuous ringing or vibrating bells of the so called "shunt" type are suited for this use; such bells being provided with windings connected to the signaling circuit, together with contacts, 75 operable by a vibrating member thereof, for alternately breaking and closing shunt paths around said windings in a well-known manner.

For the purpose of preventing unintended 80 activity of such associated manifesting stations, a current path of nominal resistance is provided in parallel with the current path of each associated manifesting station, each of such current paths serially including normally closed shunting contacts controllable 85 by an associated initiating station, so that said contacts will be separated by and during the running of the trains of such station, as, for example, being operable by 90 parts movable with the wind shafts of such trains so that, when the train of any station is in its normal fully wound condition, the shunting contacts associated therewith will be closed, and when such a train 95 is unwound more than to a predetermined extent, such contacts will be opened.

Inasmuch as the current path through the windings of each associated manifesting station is normally shunted by a parallel current path of low resistance, as just pointed out, it is evident that, while such parallel path is closed, no warning will be given, by the general manifesting mechanism included 100 in the signaling circuit, of any break in such shunted path; and that should any such path be broken, while so shunted, upon separation of the contacts included in the shunting path, by the running of the train which controls such contacts, the signaling circuit will 105 be interrupted and thus rendered incapable 110 of responding to further code signals, pending the rewinding of the train whose action broke such shunting circuit.

For the purpose of assuring the transmission of the code signal of any train which is set in motion, irrespective of the continuity of the normally shunted current path of the manifesting station associated therewith, the means for actuating the 115 shunting contacts are so constructed and arranged as to act to break said contacts only after such trains have been run down, from 120 fully wound position a distance sufficient to cause the transmission of the intended 125 code signal a predetermined one or more times.

From the foregoing it will be observed 130 that the continuity of the signaling circuit is not, at any time, dependent upon the clo-

sure of any normally open contacts; and hence that, when the train of any initiating station has been set in motion in response to the closure of controlling means contacts 5 associated therewith, the transmission of the intended code signal will not be prevented or interrupted because of any previously existing circuit defect, or because of ineffective closure of any current path, which was 10 not subject to previous continuous electrical test.

In systems employing local initiating stations of such individual resistance and under such operating conditions that, under any 15 anticipated circumstances, the resistance of the current path of the signaling circuit is likely to become so great that the normal electromotive force of the signaling-circuit current-source would be insufficient to 20 assure desired response of the signaling mechanism connected therein,—means is provided for suitably increasing the potential of said current source, whenever and so long as such increase may be needed.

25 Such means comprises automatically actuated switching mechanism controlled by the current flow in the signaling circuit so that, upon a decrease in said current flow below such a predetermined value as is 30 deemed to afford a minimum factor of safety, said means will act to cause a suitable increase in the electromotive force of the current source, and will thereafter maintain such increase until said current flow 35 has become as great as that which would result from the application of such increased potential to the resistance of the normal signaling circuit current path.

For the purpose of enabling this invention 40 to be more readily understood, an embodiment thereof is shown in the annexed drawing and hereinafter described, but this invention is not limited to the particular embodiment therein shown and hereinafter described, as various features may be employed singly, or in groups which do not comprise 45 all of the features herein described and which are illustrated in the accompanying drawing, and many changes may be made in construction and arrangement and parts 50 may be added or omitted, without departing from the spirit and scope of this invention.

Referring to the accompanying drawing, 55 in which like reference characters denote similar parts: the signaling system shown comprises a normally closed signaling circuit including signal initiating stations A, B, C and D; associated manifesting stations E, F, G and G'; a general manifesting station comprising mechanism H and I; and a current supply J, with which the mechanism K, L, M, N, O and P is associated.

Each of said initiating stations comprises means for transmitting a code signal one or

more times, which means includes make and break contacts 21 and 22, and a suitable code-wheel 23 carried by shaft 24 of a suitable train of clock-work for operating said code-wheel; these parts being omitted, in 70 the interests of clearness, in the representation of station D. Each of said trains comprises a wind shaft 25 to which a stop arm 26 is firmly secured. A stop screw 27 is mounted in the path of the arm 26, for suitably limiting the rotation of said arm with the shaft 25. An electro-magnet, having the windings 28, diagrammatically illustrated in connection with stations A, B and C, is provided for controlling the said train, so that, 80 when said train has been wound up, the effective energization of such magnet will cause said train to be set into motion for one or more complete revolutions of the code-wheel; it having been found that, for the 85 purposes of this invention, best results are most readily obtained by applying the two differential windings in interposed relation, as diagrammatically indicated by the drawing, instead of applying separate coils, as has 90 been more frequently done in the past.

Features of the construction and arrangement of the clock-work trains which are not specifically shown in the drawing, form no 95 part of this invention, and can be supplied in any of various well-known forms, the relative suitability of which will be readily perceived by those skilled in this art. Further illustration of such features is omitted in the interests of simplicity and clearness. 100

Means are provided at initiating stations 105 for controlling associated manifesting stations. Such means comprises the contacts 29 and 30, and the cam 31 which is secured to and rotates with the wind shaft 25. Each 110 of said cams is so formed as to act upon the contact 29 associated therewith to establish a connection, between said contact and the contact 30 co-operating therewith while the shaft 25 is in fully wound position and, during initial movement from said fully wound position to the position occupied by said shaft after the transmission of the intended code signal a predetermined one or more times.

Each of said cams is further so formed that, throughout all unwinding movement thereof after the aforesaid initial movement, the co-acting contact 29 will be permitted to move away from the contact 30 associated 120 therewith.

The connection between the winding shaft 25 and the code-wheel shaft 24 is so arranged that, in moving shaft 25 to wind the train, only such movement will be effective as 125 winds the train for one or more complete rotations of the shaft 24.

The transmitting stations A, B and C each have terminals 32, 33, 34, 35 and 36; the terminal 32 of each station being connected 130

through conductor 37 to one end of one of the differential windings 28 of such station, the terminals 33 and 34 being connected through the conductors 38 and 39 to respective ends of the other of such windings, and terminals 35 and 36 being connected through conductors 40 and 41 to contacts 29 and 30 respectively.

The conductor 42 of each station connects 10 contact 21 with the remaining end of the differential winding 28 and conductor 43 connects contacts 22 and 29.

For convenience of representation, the manifesting stations E, F and G are shown 15 in the accompanying drawing as vibrating bells; and the sub-station G' is indicated by the symbol for an incandescent lamp. The detailed construction of such bells and lamp form no part of this invention, and it is obvious that other forms of manifesting mechanism may, if desired, be readily employed 20 in lieu of such bells and lamp. In any event, such manifesting devices should be of a type the operation of which will not cause 25 interruptions or serious fluctuations in the current flow therethrough; such manifesting mechanisms as incandescent lamps, or vibrating bells or horns of other than the interrupter type, being suitable for such use, 30 while ordinary vibrating bells and buzzers, and other mechanism of the interrupter type, are unsuited for such use.

One terminal of the bell E is connected to a terminal of bell F through the conductor 35 44. The remaining terminals of said bells being connected through the conductors 45 and 46 to the terminals of 35 of initiating stations A and B respectively; and the terminals 36 of said stations are connected 40 through the conductor 47, which serially includes the contacts 29 and 30 of station D.

The terminals of the bell G are connected through the conductors 48 and 49 and lamp G' to terminals 35 and 36 of initiating station C.

The foregoing connections between initiating and associated manifesting stations serve, in a manner which will be hereinafter more fully explained, to render both bells 50 E and F responsive to breaks between the shunting contacts 29 and 30 of any one of the stations A, B or D; while bell G and lamp G' are alone responsive to breaks between the shunting contacts of station C.

It is evident that many adaptations of the arrangements shown may be made to suit 55 various conditions, as for example, by connecting additional bells, lamps or other suitable manifesting mechanism in series with a conductor 48, so that several varieties of manifestation (such as both visible and audible) or manifestations at a plurality of locations may be made responsive to a single initiating station; or by similarly increasing or by decreasing the number, or

altering the nature of manifesting mechanism connected in series with a conductor 44 for similar response to a group of initiating stations such as the stations A, B and D; or by omitting the station D or by connecting the shunting contacts 29 and 30 of additional initiating stations (such as the station D) in series with a conductor 47 between a pair of initiating stations such as A and B, so that such additional station or stations may similarly control the continuity of the current path through such conductor and thereby render the associated manifesting mechanism responsive to breaks between the shunting contacts 29 and 30 of any one of 80 a group of initiating stations comprising more than two of such stations.

Mechanisms comprising contacts 50 and 51 arranged in co-operating pairs, are shown 85 in associated relation with each of the initiating stations for short circuiting one of the differential windings thereof. Such mechanisms may comprise any desired manually or automatically operable means for closing a pair of normally open contacts, but, for 90 the purposes of this invention, it is merely requisite that such mechanisms shall comprise two normally disengaged conductors operable to be brought into conductive relation with one another.

Each co-operating pair of the contacts 50 and 51 are conventionally represented as comprising a thermostatically controlled circuit closing device, the contact 50 of which is normally insulated from the contact 51; such construction being provided as to cause said contacts to be moved into conductive relation one with the other when such device is influenced by certain predetermined temperature conditions; and each 100 of said contacts consisting of a unitary conducting structure having two points of connection for line conductors; so that the current path between any such two points will 105 traverse such structure.

The devices comprising the pairs of contacts 50 and 51 may be located at various points, as desired; the conducting structure of each of said devices being respectively connected in the normal current paths of the 115 signaling circuit which lead to the ends of one of the differential windings 28 of the initiating station which should be responsive thereto; to the end that the closure of any pair of said contacts will short-circuit 120 such winding, and for the further purpose of making the normal continuity of the signaling circuit dependent upon the maintenance of such connection of said contacts in said circuit as will assure their effectiveness for short-circuiting such winding.

A recording device H and a sounding device I are shown serially connected in the 125 signaling circuit, as conventional representations of a general manifesting station 130

mechanism, such as might be provided for at a central office, or elsewhere as desired. Said recording device being arranged to act upon each interruption of the signaling circuit, to suitably mark its paper tape and to condition the feeding or propelling mechanism for such tape for predetermined operation thereof, and the sounding device 1 being arranged to sound upon each such 10 interruption. It is evident that other general manifesting stations may be similarly connected.

The current supply J is arranged to furnish the needful energy for maintaining a 15 suitable current flow through the normal current path of the signaling circuit.

Said current supply should comprise means (such as, for example, a suitable number of secondary battery cells) having such 20 characteristics that, when a source of energy of higher electromotive force is connected in parallel therewith, such current supply will develop a counter electromotive force, suitably exceeding the normal discharge electromotive force of said supply, without permitting an undesirably great current flow in reverse direction through said supply.

The generator terminals of the motor-generator K are connected through conductor 62, under-voltage-release relay N, 30 conductors 63, 60, 53 and 64, (including resistances O and P) in parallel with the terminals of current source J, the controlling magnet of said relay N being permanently 35 connected to the terminals of said generator through conductors 62 and 65.

In cases when the counter electromotive force of the source J would be insufficient, in the absence of an objectionably great 40 reverse current flow therethrough, to maintain a suitable current flow in the signaling circuit under any condition for which it is deemed prudent to make provision,—a suitable resistance O will serve to permit the 45 application of a suitably increased potential to the signaling circuit between the junctions therewith of the conductors 63 and 64, without causing an objectionable reverse current flow. In cases when such counter 50 electromotive force is deemed to be sufficient for all purposes, the resistance O may be omitted.

The relay N is of the self-closing type, being arranged to so govern a connection 55 between the conductors 62 and 63 as to close such connection while the potential generated by the motor-generator K exceeds, in not less than a predetermined degree, what is assumed to be the maximum discharge potential of the source J; and to 60 thereafter open such connection when said generated potential falls to or below said discharge potential.

The resistance P serves to limit the energy 65 applied by the motor-generator K to the

source J and to the signaling circuit; thereby facilitating the utilization of a motor-generator arranged to develop an electromotive force substantially greater than that required for either suitably charging such 70 source or providing for normal operation of such circuit, and supplementing the resistance O in limiting the electromotive force which will be effective at the winding of the relay N during any normal discharging condition of the source J, as compared to the minimum electromotive force of the motor-generator K which will effect charging of such source. When the resistance O is comparatively small or is omitted (as in 75 a case when the associated manifesting stations, like E, F and G for the inclusion of which in the signaling circuit extra potential should be available, have little resistance 80 in comparison to that of the entire normal current path of said circuit),—the resistance P should be comparatively great, so as to assure a desirable range of operative adjustments for the relay N. When the resistance O is comparatively great,—the resistance P may be correspondingly decreased 85 and, in extreme cases, omitted.

The resistance P further serves to limit the abnormality of charging current flow in the event that the motor-generator is started 90 after having failed to act for a period sufficient to permit discharge of the source J to a point at which the counter-electromotive force of such source would be exceptionally 95 low.

A relay M is serially included in the signaling circuit, said relay being arranged to act through the automatic switch L to control the supply circuit comprising the conductors 71, 72 and 73, through which suitable energy may be conducted to the motor-generator K.

The automatic switch L is interposed between the relay M and supply circuit conductors 71 and 72, for the purpose of enabling said relay to be so constructed as to absorb a comparatively small amount of energy from the signaling circuit, and so as to be adjustable to act in response to comparatively small changes in the current 110 strength of said signaling circuit; while providing contacts of substantial proportions for controlling said supply circuit.

If the current of the supply conductors 71, 72 and 73 is suitable for connection directly to the signaling circuit, the motor-generator K may be omitted, the conductors 72 and 73 being, in such case, directly connected to conductors 65 and 62 respectively.

The operation of the system shown in the 125 accompanying drawing is as follows:

Under normal conditions, the trains of all the initiating stations will be fully wound, the shunting contacts 29 and 30 of such stations being held closed by their co- 130

operating cams 31, as indicated at stations B, C and D. The contacts 50 and 51 of the various circuit closing devices stand open, the contacts 20 and 21 of each of the initiating stations are held closed by the respective co-acting code-wheels 23, the current supply J causes a current flow through the signaling circuit of sufficient strength to effectively energize the controlling magnets of the various initiating and manifesting stations and to hold the armature of relay M in attracted position. Inasmuch as the normal current path includes both of the differential windings 28 of the tripping magnets of each of the initiating stations, none of said magnets will be energized, and the mechanism controlled thereby will be at rest.

The normal signaling circuit current path is as follows:—

From supply J, through conductors 53 and 54, recording device H, conductor 55, relay M, conductor 56, sounding device I, conductor 57 (and the serially included contacts 51 of the circuit closing devices of station B), to terminal 34 of station B; thence through conductor 39, one of the differential windings 28 and conductor 38 to terminal 33 of said station, thence through conductor 52 (and the serially included contacts 50) to terminal 32 of such station; thence through conductor 37, the other differential winding 28, conductor 42, make and break contacts 21 and 22, and conductor 43 to shunting contact 29 of said station B. Two normal current paths are normally provided between the shunting contacts 29 of stations B and A; one of said paths comprising the conductor 40, terminal 35, conductor 46, bell F, conductor 44, bell E, conductor 45, terminal 35, of station A and conductor 40; the other of said paths comprises the shunting contact 30, conductor 41, and terminal 36 of station B, conductor 47 (and the serially included contacts 29 and 30 of station D) and the terminal 36, conductor 41, and shunting contact 30 of station A. As the resistance of the current path through shunting contacts 30, conductors 41, terminals 36 and conductor 47 is negligible in comparison with the resistance of the current path in parallel therewith which includes the bells E and F, it is evident that substantially all of the line current will pass through such low resistance path, and that the current flow through said bells will be insufficient to cause the actuation thereof.

From the shunting contact 29 of the station A, the signaling circuit current path proceeds through conductor 43, make and break contacts 22 and 21, conductor 42, one of the differential windings 28, conductor 37, terminal 32, conductor 52 (and serially included contacts 50), terminal 33, conductor 38, the other differential winding 28,

conductor 39, to terminal 34 of said station; thence through conductor 58 (and serially included contacts 51) to one terminal of bell G.

From the terminal of the bell G to which conductor 58 is connected, two parallel current paths are normally provided to shunting contact 29 of station C. One of said paths comprises the conductor 49, terminal 36, conductor 41 and shunting contact 30 of station C; the other of said paths includes the bell G, conductor 48 (and the serially included lamp G'), terminal 35, and conductor 40 of said station. From the foregoing it will be seen that the bell G and lamp G', like bells E and F, are normally short circuited.

From shunting contact 29 of station C, the signaling circuit current path returns to the other terminal of supply J through terminal 34, conductor 59 (and serially included contacts 51), resistance O and conductor 60.

The armature of relay M being in energized position, the supply circuit for the motor-generator K is broken at the automatic switch L, and said motor-generator is at rest. The motor-generator K being at rest, relay N stands open as shown, thus preventing discharge of the supply J either through the motor-generator K or the relay N.

Assuming that a pair of the contacts 50 and 51 of station C are now closed, it is evident that the differential winding 28 connected between terminals 33 and 34 of said station will thereby be short circuited, thus rendering the winding connected between terminal 32 and contact 31 effective, so as to cause the train to be released and thereby rotate the code-wheel 23 thereof. As said code-wheel revolves, suitable breaks and closures of the signaling circuit will be caused by the actuation of the contacts 21 and 22, and the intended code signal will be manifested by the recording device H and sounding device I in a well-known manner.

It will be noted that short circuiting one of the windings 28, as just described, will result in an appreciable reduction in the resistance of the current path of the signaling circuit, and the current flow through the effective winding of the tripping magnet will therefore be somewhat greater than the normal current flow in the signaling circuit. The benefit of such an increase in current flow, at a time when it is desired to effectively energize the tripping magnet of an initiating station, will be readily appreciated by those skilled in this art.

Upon the first of the breaks between contacts 21 and 22, just referred to, relay M will act to cause automatic switch L to close the supply circuit for motor-generator K. Said motor-generator will thereupon start

- and upon generating a potential suitably exceeding that of supply J, will cause the relay N to act to connect conductors 62 and 63, and thereby apply suitable charging current to the storage battery cells of supply J through the following current path:— from one terminal of motor-generator K, through conductor 62, relay N, conductor 63 to junction of said conductor with conductor 59; thence through conductor 59, resistance O, conductor 60, secondary cells of supply J, conductor 53 and conductor 64 (and included resistance P) to the other terminal of motor-generator K.
- Upon such application of charging current to the cells of source J, a counter electromotive force will be built up in said cells and the fall of potential between the terminals of resistance O will serve to increase the potential applied to the signaling circuit (instead of decreasing such potential, as is the case while the current flow in said circuit is applied by the source J). From the foregoing it will be apparent that, while the motor-generator K is thus acting, the current flow in the signaling circuit will be supplied by said motor-generator at a potential which will be substantially in excess of the normal discharge potential of the supply J. It is also evident that if there is a proper relation between the potential generated by the motor-generator K, the resistances O and P, and the counter electromotive force developed by the supply J in consequence of the resulting charging current; sufficient potential may be supplied to the signaling circuit to insure the maintenance of a current flow at least as great as that normally supplied in said circuit, even if the resistance of one, two, or such greater number of manifesting stations as it is deemed prudent to provide for, shall be added to the resistance of the normal current path of such circuit.
- After the signal of the code-wheel 23, has been transmitted a predetermined one or more times, as just described, the face of the cam 31 will be withdrawn from the path of shunting contact 29, and said contact will thereupon move away from contact 30, thereby interrupting the short circuit around the bell G and lamp G'. After such interruption of such shunt, all current flow of the signaling circuit will pass through said bell G and lamp G' until such time as the wind shaft 25 of station C is so turned as to cause the cam 31 to move contact 29 into conductive relation with contact 30.
- As a result of such interruption of the short circuit around bell G and lamp G', said bell and lamp will thereafter ring and light, respectively continuously (except during intervals, if any, during which the make and break contacts 21 and 22 of any initiat-

ing station may interrupt the signaling circuit incident to the transmission of a signal therefrom) until the train is rewound.

Although interruption of the short circuit around the bell G and lamp G' will add the resistance of said bell and lamp to the resistance of the normal current path of the signaling circuit, such added resistance will be overcome by the increased potential supplied to the signaling circuit by the motor-generator K, and the current flow during such effective energization of the bell G and lamp G' will therefore be maintained at a strength at least as great as that normally provided in the signaling circuit.

If, at the time that the short circuit around the bell G and lamp G' is interrupted, as just described, the current path through the bell G, lamp G', conductor 48, terminal 35 or conductor 40 is broken at any point, the current flow through the signaling circuit will be thereby interrupted, and no further code signals can thereafter be transmitted over the signaling circuit until this train has been rewound or the interruption in said current path has been repaired. Although the current path a break in which may thus disable the signaling circuit is not under electrical test when the system is at rest, (and such an interruption will therefore not be manifested until the short circuit around this current path has been interrupted), the development of such an interruption will not prevent the transmission of the intended code signal to the mechanism H and I of the general manifesting station, inasmuch as such code signal will have been transmitted one or more times (depending upon the arrangement of the train which has been provided) before said short circuit is interrupted.

Initiating stations A, B and D may be correspondingly set in motion, as by closing any pair of contacts, such as 50 and 51 associated with either of said stations respectively; and the running of the train of any of these stations will, upon the separation of the shunting contacts 29 and 30 thereat, render bells E and F effective.

So long as one or more of the bells E, F and G are active, the energization of relay M will be insufficient to cause the automatic switch L to act to disconnect the motor-generator K from the power circuit; but when all of the trains are rewound, thereby short circuiting the bells E, F and G and lamp G',—the resistance of the current path of the signaling circuit will be restored to normal, and the extra potential supplied to said circuit by the motor-generator K will thereupon cause such degree of energization of the relay M as will result in the actuation of the automatic switch L to break the supply circuit of the motor-generator K, whereupon said motor-generator will stop, and

during the decrease of the potential between conductors 62 and 65 incident to such stoppage, the relay N will act to interrupt the current path between said motor-generator 5 and the signaling circuit, whereupon all parts of the system will again be in normal condition.

Should any one of the contacts 50 or 51 become disconnected from the signaling circuit, said circuit will be interrupted, and such interruption will be manifested by the mechanism H and I of the general manifesting station, and will be further manifested by the continuous operation of the 15 motor-generator K. It is therefore apparent that maintenance of operable relation, between the circuit closing devices comprising the various contacts 50 and 51 and the respective initiating stations which should 20 be responsive thereto, may be relied upon during absence of activity of the general manifesting mechanism H and I; and that, during such inactivity, the silence of the associated manifesting devices similarly indicates that the initiating stations associated 25 therewith are sufficiently wound to assure the transmission therefrom of the intended code signal in the event of the closure of any pair of the contacts 50 and 51 to which 30 such station should be responsive.

Should the short circuit current path around any associated manifesting station be accidentally interrupted, warning of such interruption will be given by the associated 35 manifesting station.

If the current supply J consists of secondary battery cells, the relay M may be utilized for automatically maintaining such cells in sufficiently charged condition, as this 40 relay may be adjusted so that, if the discharge potential of such cells falls below a predetermined value, said relay will act to start the motor-generator K; and so that, whenever said relay has, for any reason, 45 acted to cause the motor-generator K to start, said relay will not, thereafter, act to cause said motor-generator to be stopped until the current flow in the signaling circuit is such as would result from the application 50 of the charging current to the secondary cells when said cells are in fully charged condition.

Having fully described this invention, what I claim and desire to secure by Letters 55 Patent of the United States is:—

1. In a signaling system: a signaling circuit comprising a source of energy; a plurality of signal initiating stations each comprising means, including make and break contacts, for transmitting a code signal one or more times, a differentially wound magnet connected in said circuit for controlling said means, and shunting contacts operable by said means after a code signal 60 has been transmitted a predetermined one 65

or more times, said windings and contacts being serially included in said circuit and signal manifesting stations connected to said circuit in such relation to said shunting contacts that one or more of said manifesting stations will be responsive to all signals transmitted over said circuit and other of said manifesting stations will be normally unresponsive to said circuit, the relationship of said other manifesting stations to said transmitting station shunting contacts being such that the operation of the shunting contacts of any transmitting station will render a predetermined one or more of said other manifesting stations responsive to said circuit. 70 75 80

2. In a signaling system: a signaling circuit including initiating stations and associated manifesting stations; signal transmitting mechanism at each initiating station comprising means for producing groups of breaks and closures of said circuit in accordance with a predetermined code and means whereby the resistance of said circuit effective during such closures is increased 85 90 95 substantially above normal after a predetermined one or more of said groups have been transmitted; current supply mechanism connected to said circuit and normally applying thereto a potential sufficient to maintain a current flow adequate to cause intended response of manifesting stations to closures thereof when the resistance of said circuit has not been increased by the action of any of said transmitting mechanisms; and means, responsive to breaks of said circuit, for increasing the potential of said current supply mechanism throughout the ensuing groups of breaks and closures so as to cause said suitable current flow during 100 105 closures of such groups when the resistance of said circuit has been so increased.

3. In a signaling system: a signaling circuit including initiating stations and associated manifesting station; signal transmitting mechanism at each initiating station comprising means for producing groups of breaks and closures of said circuit in accordance with a predetermined code and whereby the resistance of said circuit effective during said closures is increased substantially above normal after a predetermined one or more of said groups have been transmitted; current supply mechanism connected to said circuit and normally applying thereto a potential sufficient to maintain a current flow adequate to cause intended response of manifesting stations to closures thereof, when the resistance of said circuit has not been increased by the action of any of said transmitting mechanisms, and means responsive to breaks of said circuit for increasing the potential of said current supply mechanism throughout the ensuing groups of breaks 110 115 120 125 130

and closures so as to cause said suitable current flow during closures of such groups when the resistance of said circuit has been increased as hereinbefore described, said 5 means being adjusted to maintain such increased potential while the resistance of said circuit is so increased.

4. In a signaling system: a signaling circuit including initiating stations and associated manifesting stations of substantial resistance; signal transmitting mechanism at each initiating station comprising means for operatively excluding an associated manifesting station from said circuit and 15 for operatively including such manifesting station in said circuit whenever said mechanism has completed a predetermined cycle of action, whereby said circuit is subjected to substantial increase in resistance during 20 the action of such transmitting mechanism; a current source included in said circuit and having sufficient normal potential to maintain a line current flow adequate to cause intended response of manifesting 25 stations to signaling closures through the resistance of the normal current path of said circuit; and means for increasing the potential of said current source responsive to abnormal conditioning of said circuit incident to said predetermined cycle of action 30 of any transmitter.

5. In a signaling system; a normally closed signaling circuit; signal initiating stations each comprising a windable train 35 and signaling contacts operable by said train and included in said circuit; manifesting mechanisms for each of said stations, respectively, said manifesting mechanisms being operable by the intended line current 40 of said circuit and being included in normally de-energized loops; means controlled by each of said windable trains, respectively, for energizing the associated manifesting mechanism loop from said circuit whenever 45 such train has become unwound beyond a predetermined extent, and for de-energizing such loop at other times; a current source included in said circuit and of sufficient normal potential to maintain the intended current flow therein when said associated loops are de-energized; and means controlled by the current flow in said circuit for so increasing the potential of said 50 current source as to be capable of maintaining such intended current flow in said circuit while any of said loops are energized.

6. In a signaling system; a normally closed signaling circuit; signal initiating 60 stations each comprising a windable train and signaling contacts operable by said train and included in said circuit; manifesting mechanisms for said stations, respectively, said manifesting mechanisms being 65 operable by the intended line current

of said circuit and being included in normally de-energized loops; means controlled by each of said windable trains, respectively, for including the associated manifesting mechanism loop in said circuit 70 whenever such train has become unwound beyond a predetermined extent and for de-energizing such loop at other times; a secondary battery included in said circuit and having sufficient normal potential to 75 maintain the intended current flow therein when said associated loops are de-energized; a supply circuit for said battery; and governing mechanism for said supply circuit, said mechanism being so controlled by said 80 signaling circuit as to apply suitable charging current to said battery whenever the current strength of said signaling circuit is decreased below a predetermined point and to thereafter maintain the application 85 of such charging current until the current strength in said signaling circuit is increased above a predetermined point.

7. In a signaling system: a normally closed signaling circuit; signal initiating 90 stations each comprising a windable train and signaling contacts operable by said train and included in said circuit; manifesting mechanisms for each of said stations, respectively, said manifesting mechanisms being operable by the intended line current of said circuit and being included in normally de-energized loops; means controlled by each of said 95 windable trains, respectively, for including the associated manifesting mechanism loops in said circuit whenever such train has become unwound beyond a predetermined extent and for de-energizing such loops at other times; a current source included in 100 said circuit and of sufficient normal potential to maintain the intended current flow therein when said associated loops are de-energized; a relay controlled by said signaling circuit; and an independent supply circuit so controlled by said relay as to be applied in parallel with said current source whenever the current strength of said signaling circuit is decreased below a 105 predetermined point, and to thereafter maintain such application until the current strength in said signaling circuit is increased above a predetermined point.

8. In a signaling system: a normally closed signaling circuit; signal initiating 110 stations each comprising a windable train and signaling contacts operable by said train and included in said circuit; manifesting mechanisms for each of said stations, respectively, said manifesting mechanisms being operable by the intended line current of said circuit and being included in normally de-energized loops; means controlled by said windable trains, respectively, for including such an associated manifesting 115

mechanism loop in said circuit whenever such train has become unwound beyond a predetermined extent and for de-energizing such loop at other times; a current source included in said circuit and of sufficient normal potential to maintain the intended current flow therein when said associated loops are de-energized; a relay controlled by said signaling circuit, and an independent supply circuit so controlled by said relay as to be applied to said current source whenever the current strength of said signaling circuit is decreased below a predetermined point, and to thereafter maintain such application until the current strength in said signaling circuit is increased above a predetermined point, said independent circuit being so applied to said current source as to suitably increase the potential applied to said signaling circuit.

9. In a signaling system: a normally closed signaling circuit; signal initiating stations each comprising a windable train and signaling contacts operable by said train and included in said circuit; manifesting mechanisms for said stations, respectively, said manifesting mechanisms being operable by the intended line current of said circuit and being included in normally de-energized loops; means controlled by said windable trains, respectively, for including the associated manifesting mechanism loop in said circuit whenever such train has become unwound beyond a predetermined extent and for de-energizing such loop at other times; a secondary battery included in said circuit and having sufficient normal potential to maintain the intended current flow therethrough when said associated loops are de-energized; a motor-generator adapted to supply energy to said battery at such a rate as to suitably increase the potential available for the energization of said signaling circuit; an automatic switch governing a connection between said motor-generator and said battery so that said connection will be effective while the potential of said motor-generator is sufficient to cause a suitable increase of the potential applied to said signaling circuit; a supply circuit for said motor-generator; and governing mechanism for said supply circuit, said mechanism being so controlled by said signaling circuit as to apply suitable operating current to said motor-generator whenever the current strength of said signaling circuit is decreased below a predetermined point, and to thereafter maintain the application of such operating current until the current strength in said signaling circuit is increased above a predetermined point.

10. In a signaling system: a normally closed signaling circuit; signal initiating stations each comprising a windable train

and signaling contacts operable by said train and included in said circuit; manifesting mechanisms for said stations, respectively, said manifesting mechanism being operable by the intended line current of said circuit and being included in normally de-energized loops; means controlled by said windable trains, respectively, for including the associated manifesting mechanism loop in said circuit whenever such train has become unwound beyond a predetermined extent and for de-energizing such loop at other times; a secondary battery included in said circuit and having sufficient normal potential to maintain the intended current flow therein when said associated loops are de-energized; a resistance included in said circuit adjacent to said battery; a motor-generator adapted to supply energy to said battery through said resistance at such a rate as to suitably increase the potential available for the energization of said signaling circuit; connections whereby the energy of said motor-generator may be suitably applied to said battery through said resistance; an automatic switch for rendering such connections effective while the potential of said motor-generator is sufficient to maintain the intended current flow in said circuit through a predetermined number of said associated loops; a supply circuit for said motor-generator; and governing mechanism for said supply circuit, said mechanism being so controlled by said signaling circuit as to cause suitable operating current to be supplied to said motor-generator whenever the current strength of said signaling circuit is decreased below a predetermined point, and to thereafter maintain the application of such operating current until the current strength of said signaling circuit is increased above a predetermined point.

11. In a signaling system: a signaling circuit comprising a source of energy; a plurality of signal transmitters each comprising code transmitting contacts and a differentially wound controlling magnet, said contacts and the windings of said magnets being serially included in said circuit; one or more mechanisms associated with each of said transmitters, respectively, each of such mechanisms comprising a pair of normally open contacts one of which is serially included in a portion of said circuit at one side of one of the windings of some one of said differential magnets and which is serially included in a portion of said circuit at the other side of such winding; and signal manifesting means included in said circuit.

12. In a signaling system: a signaling circuit comprising a source of energy; a plurality of signal transmitters each comprising code transmitting contacts and a differentially wound controlling magnet, said contacts and the windings of said magnets being

- serially included in said circuit; mechanisms each comprising a pair of normally separated contacts closable by an associated one of said transmitters, the contacts of each pair 5 serially included in said circuit at one side and the other, respectively, of one of the differential windings of its associated transmitter, and signal manifesting means included in said circuit.
- 10 13. In a signaling system: a plurality of signal transmitters each comprising code transmitting contacts, normally closed shunting contacts and a differentially wound controlling magnet; a signaling circuit comprising a source of energy and 15 serially including said contacts and the windings of said magnets together with means associated with each transmitter for establishing a short circuit around one of the differential windings of the controlling 20 magnet thereof; signal manifesting means connected in parallel with the shunting contacts of each of said transmitters, respectively; and means moved by such transmitters, after predetermined operation thereof, 25 to separate the shunting contacts associated therewith.
14. In a signaling system: a signaling circuit comprising a source of energy; a plurality of signal transmitters each comprising code transmitting contacts and a differentially wound controlling magnet, said contacts and the windings of said magnets being 30 serially included in said circuit; mechanisms each comprising a pair of normally separated contacts closable by an associated one of said transmitters, the contacts of each pair serially included in said circuit at one side and the other, respectively, of one of the differential windings of its associated 35 transmitter; normally closed shunting contacts for each of one or more of said transmitters, said contacts being serially included in said signaling circuit; means moved by 40 such transmitters, after predetermined operation thereof, to separate the shunting contacts associated therewith; and signal manifesting means connected in parallel with said shunting contacts.
- 45 15. In a signaling system: a signaling circuit comprising a source of energy; a plurality of signal transmitters each comprising code transmitting contacts and a differentially wound controlling magnet, said contacts and the windings of said magnets being 50 serially included in said circuit; mechanisms each comprising a pair of normally separated contacts closable by an associated one of said transmitters, the contacts of each 55 pair serially included in said circuit at one side and the other, respectively, of one of the differential windings of its associated transmitter; normally closed shunting contacts

for each of one or more of said transmitters, 65 said contacts being serially included in said signaling circuit; means moved by such transmitters, after predetermined operation thereof, to separate the shunting contacts associated therewith; signal manifesting means connected in parallel with said shunting contacts; and signal manifesting means 70 included in said circuit other than in parallel with any of said contacts.

16. In a signal transmitter,—a normally wound train, differentially wound electro-magnetic releasing means for said train, 75 normally closed code signaling contacts operable by said train to formulate a predetermined code one or more times, normally closed shunting contacts so controllable by 80 said train in running as to remain closed during initial action thereof to formulate such code one or more times, and to be thereafter held open during action of said train to formulate said code signal an additional 85 one or more times, and suitable conductors serially connecting one of said magnet windings, the signaling contacts and the shunting contacts.

17. In a signal transmitter,—a normally 90 wound train, electro-magnetic releasing means for said train comprising a differentially wound magnet, a code-wheel revoluble by said train, normally closed signaling contacts controlled by said code-wheel, normally 95 closed shunting contacts separable during the running of said train after one or more revolutions of the code-wheel, five binding posts, two of which are directly connected to the respective ends of one of said magnet 100 windings, the other of said windings, and the code-wheel contacts being serially connected between another of said binding posts and one of the shunting contacts, the other two of said binding posts being connected to 105 said shunting contacts, respectively.

18. In a signal transmitter,—a normally wound train, differentially wound electro-magnetic releasing means for said train, normally closed signaling contacts operable by said train to formulate a predetermined code one or more times, normally closed shunting contacts separable during the running of said train after the code has been 110 formulated one or more times, five binding posts between two of which is connected one of said magnet windings, between another two of which are connected the shunting contacts, and between the other one of which posts and one of said shunting contacts are 115 serially connected the other one of the magnet windings and the signaling contacts.

In witness whereof, I hereunto subscribe my name, this 7th day of October, 1919.

C. E. BEACH.
